G. W. HANLON.
SKATE SHARPENER.
FILED FEB. 8, 1922.

UNITED STATES PATENT OFFICE.

GEORGE WM. HANLON, OF DARBY, PENNSYLVANIA.

SKATE SHARPENER.

Application filed February 8, 1922. Serial No. 535,061.

To all whom it may concern:

Be it known that I, GEORGE WM. HANLON, a citizen of the United States, residing in the city of Darby and State of Pennsylvania, have invented new and useful Improvements in Skate Sharpeners, of which the following is a specification, reference being had to the accompanying drawings.

The invention is a skate sharpener, and 10 the object it to provide a simple and practical hand operated sharpener for ice skates. Devices for the same purpose have heretofore been patented, but they all employ a file as the abrading or sharpening element, 15 which file soon becomes dull, rendering the sharpener useless; likewise where a file sharpener is employed only the forward thrust is effective. In the present tool a whet stone is employed as the sharpening element, 20 whereby both the forward and backward strokes are rendered equally effective. Another advantage of the use of the stone is that it wears away very gradually, and can be used successfully as long as any part of the 25 stone remains in the holder; and when one stone wears out, another may be substituted in the holder. Another advantage is that guideways are provided both along one side of the tool and at the ends, for interchangeable use.

In the drawings:

Figure 1 is a perspective view showing the sharpener positioned upon the blade of a skate, as for sharpening.

Figure 2 is a side view of the sharpener. Figure 3 is a top view.

Figure 4 is an end view.

The invention consists of a flat and rectangular whet stone 1, of a thickness approximately equal to the blade 2 of the skate 40 3. Metal guide plates 4, of substantially

greater length and width than the whet stone 1, are positioned one at each side of the stone 1, and are releasably held and locked in that position by means of two forked clamps 5 which are forced over the guide plates at each end, thus pinching the stone 1 between the plates 4. The blade 2 is positioned within either the guide ways 6 or 7 so formed, and against the stone 1. Drawing the 50 sharpener back and forth along upon the blade 2, sharpens the latter. Likewise the end guide ways 7 may be used, as desired. The stone 1 may be replaced quickly by removing the clamps 5. In use the whet stone 55 is found to give better results than a file, lasts much longer, takes hold of the hard steel of the blade to better advantage than a file and does not scratch the blade as does a file. This sharpener may be made and sold 60 at a very low cost, and is very handy and convenient.

While I have herein described a certain specific method of constructing and assembling the elements of my invention, it is understood same may be varied in minor details, not departing from the spirit of my invention as defined in the appended claim.

I claim:

A skate sharpener, comprising a flat, rectangular whet stone of the approximate thickness of the skate blade; two metal guide plates of substantially greater length and width than the whet stone, and positioned one at each side thereof so as to form 70 guide-ways along one edge and at the ends; and releasable clamps for frictionally holding 75 the guide plates and stone together.

GEORGE WM. HANLON.
